UNITED STATES PATENT OFFICE.

EDWIN B. H. TOWER, JR., OF MILWAUKEE, WISCONSIN, ASSIGNOR TO BADGER MANUFACTURING CORPORATION, OF MILWAUKEE, WISCONSIN, A CORPORATION OF DELAWARE.

DESIGN FOR AN AUTOMOBILE BUMPER.

Application filed May 13, 1922. Serial No. 2,221. Term of patent 3½ years.

To all whom it may concern:

Be it known that I, EDWIN B. H. TOWER, Jr., a citizen of the United States, residing at Milwaukee, in the county of Milwaukee and State of Wisconsin, have invented a new, original, and ornamental Design for an Automobile Bumper, of which the following is a specification, reference being had to the accompanying drawing, forming a part thereof.

The figure of the drawing is an elevational view of an automobile bumper embodying the new design.

The invention claimed is:

The ornamental design for an automobile bumper as shown.

In witness whereof I have hereunto subscribed my name.

EDWIN B. H. TOWER, JR.
